(57) **CLAIM**

The ornamental design for a combined modular tomato support tower and connecting rod, as shown and described.

DESCRIPTION

FIG. 1 is an environmental perspective view of a plurality of combined modular tomato support towers and connecting rods arranged in a connected state, showing our new design; FIG. 2 is a perspective view of a modular tomato support tower with a connecting rod selectively inserted into one of a plurality of connecting rod apertures in the modular tomato support tower; FIG. 3 is an exploded perspective view of the modular support tower and connecting rod; FIG. 4 is front view thereof with a rear view being a mirror image; FIG. 5 is a left side view thereof with a right side view being a mirror image; FIG. 6 is a top view thereof; and, FIG. 7 is a bottom view thereof. The modular tomato support towers if FIGS. 1-7 are shown broken away to indicate indeterminate length. The broken line showing of a additional modular tomato towers and connecting rods shown in FIG. 1 is for the purpose of illustrating environment and forms no part of the claimed design.
